UNITED STATES PATENT OFFICE.

HENRY S. GOSNELL, OF TERRE HAUTE, INDIANA, ASSIGNOR OF ONE-HALF TO LINDS E. GOSNELL, OF WEST TERRE HAUTE, INDIANA.

DESIGN FOR A STENCIL.

41,933.

Specification for Design.

Patented Nov. 21, 1911.

Application filed August 17, 1911. Serial No. 644,697. Term of patent 14 years.

To all whom it may concern:

Be it known that I, HENRY S. GOSNELL, a citizen of the United States, residing at Terre Haute, in the county of Vigo and State of Indiana, have invented a new, original, and ornamental Design for Stencils, of which the following is a specification, reference being had to the accompanying drawing, forming part thereof.

The figure is a plan view of a stencil, showing my new design.

I claim:

The ornamental design for a stencil, as shown.

HENRY S. GOSNELL.

Witnesses:

GEORGE D. SHANNON,
GEORGE E. OSBURN.
